(57) **CLAIM**

The ornamental design for a shaver step, as shown and described.

DESCRIPTION

FIG. 1 is a perspective view of a shaver step in accordance with one embodiment;

FIG. 2 is a front view of the shaver step of FIG. 1;

FIG. 3 is a rear view of the shaver step of FIG. 1;

FIG. 4 is a left side view of the shaver step of FIG. 1;

FIG. 5 is a right side view of the shaver step of FIG. 1;

FIG. 6 is a top view of the shaver step of FIG. 1; and,

FIG. 7 is a bottom view of the shaver step of FIG. 1.

The broken line drawings of the images, text, and other elements shown in the figure are shown for illustrative purposes only and form no part of the claimed design. In addition, the surface shading, if any, illustrated in the drawings is provided merely to highlight the contour of the design; it is not intended to be illustrative of texture or gloss.
